ANTIRATTLING DEVICE FOR ANTENNA MASTS

Filed Sept. 4, 1945

UNITED STATES PATENT OFFICE

2,456,330

ANTIRATTLING DEVICE FOR ANTENNA
MASTSRussell J. Scott, Kalamazoo, Mich., assignor to
Shakespeare Products Company, Kalamazoo,
Mich., a corporation of Michigan

Application September 4, 1945, Serial No. 614,349

2 Claims. (Cl. 250—33)

1

This invention relates to improvements in radio antennas, particularly, to telescopically collapsible antennas.

An important object of the invention is to provide anti-rattling means for the telescopic sections of a radio antenna mast, whereby said sections will be prevented from having vibratory movement and resultant rattling with relation to the particular sections receiving the same.

Moreover, it is an equally important object of the invention to provide an antenna mast wherein rattling or similar vibratory movement between the telescopically engaged sections constituting the same will be prevented, irrespective of the individual positioning of said sections, i. e., whether they have been moved or adjusted to fully or partially extended positions.

In the production of telescopic types of radio antenna masts, especially, those types used upon motor driven vehicles for the reception of radio intelligence, as described and claimed in my pending application, Serial No. 596,127, filed May 28, 1945, various forms of anti-rattling devices are provided to their telescopically interengaged mast sections and it is the purpose of the same to prevent rattling or like vibratory movement thereof; also, to effect movable retention of the slideable sections in pre-selected longitudinally adjusted positions. For the better part, such devices have a limited area contact or engagement with the telescopically received section or sections, and usually, are positioned in a receiving section adjacent or near the outer end of the same. The result of such positioning in the receiving section and "spot" engagement with the telescopically received section, is that notwithstanding the fact that the latter is frictionally gripped and releasably retained in a particular longitudinally adjusted position with relation to the former, the inner portion of the telescopically received section, that is, the portion of it within the receiving section, is permitted of lateral vibratory movement or rattling within said receiving section, with the point of frictional engagement between the referred to anti-rattling device and telescopically received section affording or constituting a fulcrumming-like bearing. Not only does such a construction permit of the above mentioned objectionable rattling between the thus constituted and equipped radio antenna mast sections, but moreover, it is manifest that because of the described lateral movement or play of an inner portion of a telescopically received section within its receiving section, such movement will, invariably, result in premature wearing of the antenna

2

mast assembly and its parts, to the extent that, in a comparatively short time, the extendable sections of the mast assembly will become incapable of retaining a secure adjusted, extended or partially extended relationship, and additionally, inadequate or faulty electrical conductivity.

Through the medium of my invention, there is provided a device which will positively prevent rattling and like vibratory movement between the telescopically engaged sections of an equipped antenna mast, irrespective of the longitudinally adjusted relationship existing therebetween, i. e., whether the telescopically engaged mast section or sections is or are in telescopically collapsed, distended or partially distended position with respect to the mast section receiving the same; a device which will securely retain the adjustable section or sections in adjusted relation, and moreover, ensure constant and effectual electrical conductivity between the structural parts of the assembly.

The foregoing, as well as other objects, advantages, and meritorious teachings of the invention, will be in part obvious and in part pointed out in the following detailed disclosure thereof, when taken in conjunction with the accompanying drawings; it being understood that the particular form of invention herein is a precise and what is now considered to be the best mode of embodying its principles, but that modifications and changes may be made in specific embodiments, without departing from its essential features.

35. In the drawings:

Figure 1 is a side elevation of an antenna mast embodying the invention.

Figure 2 is an enlarged and fragmentary side elevation of the antenna mast, showing the anti-rattling device arranged in certain of the mast sections in dotted lines, and also, showing the character of engagement or reception of the telescopically received mast sections in their particular receiving sections.

45. Figure 3 is an enlarged fragmentary detail in longitudinal section, showing the manner in which telescopic engagement is effected between certain of the mast sections, and moreover, the mode of engagement of one end of one of the anti-rattling devices in the upper end of its particular section.

Figure 4 is a fragmentary longitudinal section showing the telescopic engagement between the tubular sections of the antenna mast, and also, 55 showing the manner in which certain of the ends

of the anti-rattling devices provided thereto are disposed and connected.

Figure 5 is an enlarged fragmentary longitudinal section through the lower or basal portion of the outermost tubular section of the improved antenna mast, illustrating the manner in which the lower end of its particular anti-rattling device is secured or connected to the same.

Figure 6 is a transverse section taken on the line 6-6 of Figure 5, looking in the direction in which the arrows point.

Figure 7 is an end elevation of the lower end or basal portion of the antenna mast, illustrating the fixed connection of the lower end of the anti-rattling device provided to the outer mast section to its lower end, and

Figure 8 is an enlarged transverse section in detail, showing the cross-sectional curvature of one of the anti-rattling devices and the manner in which it is engaged with its particular or adjacent telescopically engaged antenna mast section.

Referring in detail to the drawings it will be noted that I have illustrated my invention applied to that type of antenna mast more often used on automobiles for the reception of radio intelligence transmission of audio frequencies, though, of course, its usage is not necessarily so limited. Such a mast, generally, comprises a tubular main member 1, a tubular secondary member 2 telescopically received in the latter, and a rod 3, ended as at 4, telescopically received in the member 2. Thus, a telescopic antenna mast assembly is provided.

The members 2 and 3 are extendable with relation to the tubular main member 1 and to each other, whereby a mast of the particularly desired length (limited to the over-all extendable lengths of the members 1, 2 and 3) may be produced.

In order that the mast assembly may be attached and supported, a usually though not necessarily vertically positioned mounting bracket 5 is provided and snugly receives therein the basal portion of the tubular main member 1. Suitable conductors (not shown) are provided to the mounting bracket 5 and, as will be understood, effect proper electrical conductivity between the members of the mast assembly and the radio apparatus equipped therewith.

The normally outer end portions of the tubular main and the tubular secondary members 1 and 2, are annularly reduced or constricted, as indicated at 1' and 2'. Thus, the main body portion of the member 2 is comparatively snugly and slidably received in and through the reduced end portion 1' of the member 1, and the similar portion of the rod 3 is likewise slidably received in and through the reduced end portion of the member 2.

Outward longitudinal sliding disengagement of the tubular secondary member 2 from the tubular main member 1 is prevented by annularly enlarging the normally inner end portion of the member 2, as at 2^a and snugly and slidably engaging the same within the body portion of the member 1, inwardly of its reduced portion, and by enlarging or flattening the normally inner end portion of the rod 3, as at 3^a, and slidably engaging the same within the body portion of the member 2, inwardly of its reduced portion 2', as illustrated by the Figures 2, 3, and 4 of the accompanying drawings.

To effect yieldable frictional connection be-

tween the main member 1 and the secondary member 2, a strip-like body 6 of suitable electrically conductive spring metal of transversely arcuate or curved formation, is longitudinally engaged within the member 1. This spring element is helically twisted or wound at a relatively long pitch with its transversely dished surface inwardly disposed and has the normally outer end of the same arranged adjacent the annular shoulder formed in the corresponding end of the member 1 by the aforesaid annular end reduction 1' thereof. The length of the helical spring body 6 is such that its remaining end is arranged near the adjacent and normally inner end of the member 1 where the same is blindingly engaged with and anchored by the longitudinally flattened side of an anchoring closure plug 7, fixedly received in said member end. A longitudinal screw threaded bore 8 is preferably formed in the plug 7 and is adapted to receive a connecting screw (not shown) appropriately engaging the mounting bracket 5 whereby the member 1, and hence, the antenna mast assembly, will be connected to the latter.

Because of the helical formation of the spring body 6 and its transverse area, plus its inherent spring properties, the same will maintain frictional contact with the adjacent walls of the member 2 (circumferentially thereof) substantially throughout its length, though slight longitudinal bodily adjusting movement thereof will be permitted by reason of the engagement of the inner end of the spring body with the annular internal shoulder of the reduced portion 1' of the tubular member 1.

A second strip-like spring body 9, similar in construction and formation to the strip-like spring body 6, is longitudinally engaged within the member 2. Said strip-like spring body 9 is twisted or wound at a relatively long pitch with its transversely dished surface inwardly disposed. The normally outer end of the spring body 9 is arranged adjacent the annular shoulder formed in the corresponding end of the member 2 by its annular end reduction, as at 2'. The length of this strip-like helical spring body 9 is such that its remaining end is arranged near or adjacent the corresponding and normally inner end of the member 2, i. e., its enlarged inner end portion 2^a. And to fixedly connect this remaining end of the spring body 9 to the inner enlarged end portion 2^a of the member 2, a plug 10 having a longitudinally disposed flattened side is snugly inserted into said enlarged end portion 2^a, as by driving fit, and is then locked or secured against further longitudinal movement with relation to the member 2 by peening, as at 11, or by other suitable means. It will be noted that the outer end of the plug 10 is preferably flush with the corresponding end of the enlarged portion 2^a of the member 2.

The arrangement and formation of the strip-like helical spring bodies 6 and 9 in the members 1 and 2, is such that they will individually function to frictionally contact or engage adjacent portions of the tubular secondary member 2 and the rod 3, respectively. That is to say, the intermediate portion of the strip-like spring body 6, because of its previously described mounting or arrangement within the tubular main member 1, will frictionally contact with and about that portion of the tubular secondary member 2 telescopically engaged in the latter member. Likewise, the intermediate portion of the strip-like helical spring body 9, will be fric-

tionally engaged with and about the peripheral surface of that portion of the rod 3 telescopically engaged within the tubular secondary member 2. In consequence, it will be readily understood that those portions of the member 2 and the rod 3 engaged within their respective receiving tubular members will be prevented from having relative vibratory movement, i. e., rattling, throughout their respective lengths. Moreover, it will be understood that both the tubular secondary member 2 and the rod 3 will be prevented from having fulcruming movement adjacent their respective points of entry into their particular tubular receiving members, to wit, the annularly reduced portions 1' and 2' of the tubular members 1 and 2. Such fulcruming movement, obviously, will be prevented because of the spring frictional engagement of the strip-like helical bodies 6 and 9 with the entire lengths of those portions of the secondary tubular member 2 engaged in the tubular main member 1 and the rod 3 telescopically engaged within the tubular secondary member 2.

At this point, attention is invited to the fact that a positively, accentuated frictional and a constantly yieldable contact or engagement between the strip-like helical spring bodies 6 and 9 and their respectively engaged portions of the member 2 and the rod 3, is effected by the transverse curvature of each of said bodies, hereinbefore described. The curvature of said bodies is of a greater degree than that of the outer peripheral surface of the tubular member 2 and the rod 3, as is well indicated in Figure 8 of the accompanying drawings. Therefore, it will be seen that with arrangement of these strip-like helical spring bodies 6 and 9 between the tubular members 1 and 2 and between the tubular member 2 and the rod 3, each of said bodies will be under a more or less constant tension, and so, will effect positive and increased frictional contact. Not only do the strip-like helical spring bodies 6 and 9 prevent relative vibratory movement or rattling of the telescopically engaged parts, hereinabove described, but it will also be understood and appreciated by workers skilled in this art, that said spring bodies will serve to movably though firmly retain the telescopically engaged or received secondary tubular member 2 and the rod 3 in any one of a plurality of relatively longitudinally adjusted positions, hence, insuring their satisfactory retention in fully or partially distended positions.

If desired, a suitable type of lubricant may be supplied within the tubular members 1 and 2 so that as the member 2 and the rod 3 are longitudinally moved therein, their outer peripheral surfaces will be coated with a weather resistant film, preventing corrosion, rusting or like impairment of such surfaces, and by the same

token, insuring smooth sliding during adjustment operation.

If desired, the number of tubular members may be either increased or decreased, as may their diameters and lengths. Moreover, the herein illustrated and described formation of the constricted or reduced end portions 1' and 2' of the tubular members 1 and 2, respectively, may be varied without departing from either the spirit or the scope of this invention; it being the essence of such invention to provide an anti-rattling device for telescopic sectional body assemblies wherein those portions of such sections within their particular or respective tubular receiving members will be prevented from having vibratory relative movement entirely throughout their lengths.

I claim:

1. In combination with the telescopically engaged sections of an antenna mast, a length of strip-like cross-sectionally arcuately shaped spring material in one of the sections engaged about and generally lengthwise along the adjacent portion of the other section, the degree of curvature of the cross-sectionally arcuately shaped spring material being greater than the degree of curvature of adjacent portions of the telescopically engaged sections whereby to effect yieldable and frictional contact between said strip-like material and said sections.

2. In combination with the telescopically engaged cross-sectionally circularly shaped sections of an antenna mast, a length of helically formed strip-like electrically conductive spring material of cross-sectional arcuate shape in and disposed generally longitudinally of one of said sections and spirally engaged about and along an adjacent portion of the other section, the degree of curvature of the arcuate cross-sectionally shaped strip-like spring material being greater than the degrees of the cross-sectional curvature of adjacent portions of said telescopically engaged sections, whereby to effect yieldable and frictional contact between said strip-like spring material and said sections.
